NORBERT CHAPDELAINE, OF MONTREAL, QUEBEC, CANADA, ASSIGNOR TO ALLAN ANGUS MAGEE, OF MONTREAL, QUEBEC, CANADA.

ROCKING TRICYCLE.

1,396,505.

Specification of Letters Patent.

Patented Nov. 8, 1921.

Application filed January 17, 1921. Serial No. 437,821.

To all whom it may concern:

Be it known that I, NORBERT CHAPDELAINE, a subject of the King of Great Britain, and residing at 740 Papineau avenue, in the city 5 and District of Montreal, in the Province of Quebec, in the Dominion of Canada, have invented a new and useful Rocking Tricycle, of which the following is a specification.

The invention relates to a rocking tri- 10 cycle, as described in the present specifica- 10 tion and illustrated in the accompanying drawings that form part of the same.

The invention consists essentially in the 15 novel means employed, whereby an animal shaped form rocks automatically and continuously while under way.

The objects of the invention are to afford 20 amusement for children in a wholesome and healthful manner; to produce a first class 20 toy at a moderate price well within the reach of all the people; and to provide a toy, which is simple to make and of a durable 25 nature.

In the drawings, Figure 1 is a perspective 25 view of the toy complete.

Fig. 2 is a front elevation of the toy.

Fig. 3 is a vertical section showing the rear wheel in full end view.

Fig. 4 is a perspective detail of the steer- 30 ing gear.

Fig. 5 is a perspective detail of the rock- 30 ing wheel.

Fig. 6 is a perspective detail of a front 35 wheel.

Like numerals of reference indicate corre- 35 sponding parts in each figure.

Referring to the drawings, the body 1 of the animal is cut out of a plank or made of other material.

The hind legs 2 are rigidly secured by the 40 screws 3 to the body 1 and extend rear- 40 wardly somewhat in the position of a running animal. The rear wheel 4 is placed between the hind legs 2 and the pin 5 se- 45 cures the wheel 4 to said hind legs 2, said 45 pin being fixed in the wheel 4 to one side 50 of the center and turning freely in the legs 50, so that at each revolution of the wheel 4 the body moves upwardly and downwardly 55 around the center of the wheel.

The front legs 5 are secured to the body,

by the screws 6 and at their lower ends are rigidly secured to the cross bar 7.

The cross bar 7 is pivotally secured to the steering blocks 8 by the bolts 9 and nuts 10, 55 said blocks tapering off at their frontends 11 and pivotally secured thereto the steering rod 12.

The steering post 13 is rotatably mounted 60 in the body 1 and in the bar 7 and termi- 60 nates at its upper end in the handle 14.

The pin 15 projects forwardly from the 65 post 13 through the eye 16, the latter being screwed into the rod 12, so that any move- 65 ment of the post 13 at once affects the rod 12 and consequently the blocks 8.

The blocks 8 are secured to the front 70 wheels 17 by the screws 18 and turn freely 70 on the screw shanks between the washers 19 and 20. The screws 18 enter the blocks 8 or the latter may be secured by bolts; how- 75 ever as the bar 7 must rock slightly the sim- 75 plest construction has been shown and it answers perfectly, as the blocks simply turn back on the screws slightly at each rocking motion.

In the operation of the invention the 80 child sits in the saddle with his feet resting 80 on the bar 7 and after getting a good start he can readily propel himself by the action 80 of the eccentric mounting of the body on the rear wheel or if in the case of a very small child an attendant propels the toy by a lead line then the child gets all the benefit and pleasure of the up and down motion. 85

What I claim is:—

1. A rocking tricycle comprising a body 90 in the form of an animal having rearwardly extending hind legs and a wheel pivotally secured between said hind legs with an ec- 90 centrically situated pivot in relation to the thread of the wheel, a pair of wheels sup- 95 porting the front legs, parallel bars piv- 95 otally secured at the ends and connected to said front wheels, one of said bars forming the direct support for said front legs, and a steering post suitably connected with the said parallel bars.

2. In a rocking tricycle, a body shaped as 100 an animal and having forelegs and hindlegs rigidly secured thereto, a steering post hav- 100 ing a handle and rotatably mounted in said

body, a cross bar forming a bottom bearing for said post, steering blocks having a slight rotative movement, a steering rod parallel with said bar and having a central eye projecting therefrom, a pin projecting from said post into said eye, pivots securing said bar and rod to said blocks, front wheels sup-

ported and journaled from said blocks and a rear wheel having a rigid pin therein and projecting therefrom to one side of the center and journaled in the aforesaid hind legs. ¹⁰

Signed at Montreal, Quebec, Canada, this 11th day of January, 1921.

NORBERT CHAPDELAINE.
